CLAIM

The ornamental design for an organizer rack with vertical storage sections, as shown and described.

DESCRIPTION

FIG. 1 is a front, right side and top perspective view of an organizer rack with vertical storage sections, showing my new design;

FIG. 2 is a top plan view thereof;

FIG. 3 is a front elevational view thereof, the rear elevational view being a mirror image;

FIG. 4 is a left side elevational view thereof;

FIG. 5 is a right side elevational view thereof;

FIG. 6 is a bottom plan view thereof;

FIG. 7 is a front, right side and top perspective view of a second embodiment of an organizer rack with vertical storage sections, showing my new design;

FIG. 8 is a top plan view thereof;

FIG. 9 is a front elevational view thereof, the rear elevational view being a mirror image;

FIG. 10 is a left side elevational view thereof;

FIG. 11 is a right side elevational view thereof;

FIG. 12 is a bottom plan view thereof;

FIG. 13 is a front, right side and top perspective view of a third embodiment of an organizer rack with vertical storage sections, showing my new design;

FIG. 14 is a top plan view thereof;

FIG. 15 is a front elevational view thereof, the rear elevational view being a mirror image;

FIG. 16 is a left side elevational view thereof;

FIG. 17 is a right side elevational view thereof; and,

FIG. 18 is a bottom plan view thereof.
